(57) **CLAIM**

The ornamental design for a face insert for golf club head, as shown and described.

DESCRIPTION

FIG. 1 is a front elevational view of a first embodiment of the face insert for golf club head;

FIG. 2 is a cross sectional view thereof taken along line 2-2 in FIG. 1;

FIG. 3 is cross sectional view thereof taken along line 3-3 in FIG. 1; and

FIG. 4 is an enlarged view of area 4 in FIG. 2.

FIG. 5 is a front elevational view of a second embodiment of the face insert for golf club head;

FIG. 6 is a top plan view thereof; and,

FIG. 7 is an enlarged view of area 7 in FIG. 6.

The broken lines depict parts of the face insert that form no part of the claimed design. The dot-dash chain lines depict boundaries of the claimed subject matter and form no part of the claimed subject matter. The dot-dot-dash chain lines depict cross-section lines and enlargement areas and form no part of the claimed subject matter.
